United States Patent

Des. 240,226

Patented June 8, 1976

240,226

CARTRIDGE HOLDER

Gerald D. Sjostrand, 4734 E. Home,
Fresno, Calif. 93703

Filed Jan. 10, 1975, Ser. No. 540,248

Term of patent 14 years

Int. Cl. D3—02

U.S. Cl. D22—14

FIG. 1 is a perspective view of a cartridge holder embodying my new invention.

FIG. 2 is a top plan view thereof.

FIG. 3 is a bottom plan view thereof.

FIG. 4 is a front elevation thereof.

FIG. 5 is a rear elevation thereof.

FIG. 6 is an end elevation thereof, the opposite end being of the same ornamental appearance.

I claim:

The ornamental design for a cartridge holder, as shown and described.
